UNITED STATES PATENT OFFICE

156,714

BRASSIÈRE

Olga Erteszek, Los Angeles, Calif.

Application September 13, 1948, Serial No. 148,561

Term of patent 7 years

(Cl. D20—4)

To all whom it may concern:

Be it known that I, Olga Erteszek, a citizen of the United States of America, residing at Los Angeles, in the county of Los Angeles and State of California, have invented a new, original, and ornamental Design for Brassières, of which the following is a specification, reference being had to the accompanying drawing, forming a part thereof.

The figure is a perspective view of a brassière, showing my new design.

I claim:

The ornamental design for a brassière, as shown.

OLGA ERTESZEK.

No references cited.
